a corporation of Ohio

Application October 19, 1939, Serial No. 300,147

3 Claims.

(Cl. 15—16)

This invention relates to improvements in suction cleaners and more particularly to a suction cleaner wherein the height of the nozzle above the surface being cleaned is automatically adjusted by the downward pressure exerted through the handle.

The suction cleaner embodying the novel features of the present invention is one preferably designed for use with dusting tools and hose and therefore one of the objects of the invention is to provide for the raising of the nozzle by the application of a downward pressure on the handle not only for adjusting the height of the nozzle automatically to the particular kind and quality of carpet being cleaned but equally, to elevate the nozzle clear of the carpet surface during the period of dusting tool operation and for reasons which presently will be pointed out.

A very common expedient for adjusting the height of the nozzle with respect to the carpet surface is to provide the cleaner with adjustable front or rear wheels, that is to say, wheels which can be adjusted vertically with respect to the cleaner body, although the adjustability of the wheels is usually confined either to the front or rear wheels.

In the present disclosure the adjustable wheels are located at the rear end of the cleaner and are journaled upon a support bracket having a pivoted mounting on the underside of the body. In fact, the present adjustable rear wheel mounting resembles in many respects that disclosed in Letters Patent No. 2,177,974, dated October 31, 1939.

In this earlier disclosure, the rear wheels are also journaled upon a bracket having pivotal mounting on the underside of the cleaner body and capable of being adjusted manually by an adjusting screw having a knob accessible from the upper side of the cleaner body. Moreover, relatively stiff torsion springs prevent the rear wheel support bracket from shifting about its axis and hence the cleaner body from tilting about the front wheels and raising the nozzle, except when considerable pressure is applied at the rear end of the cleaner by the operator and for the express purpose of converting the cleaner to dusting tool operation. In other words, no adjustment in the nozzle height during normal carpet cleaning operation is contemplated except by manipulating the manual adjustment.

Moreover, to convert the cleaner from so-called "on-the-floor" cleaning to "off-the-floor" cleaning by means of the dusting tools, it is neces-

sary, as in the present arrangement, to insert a special converter fitting, carried at one end of the dusting tool hose, into a laterally opening port at one side of the cleaner body and by this operation connect the dusting tool hose directly with the source of suction. Likewise, it is desirable that the nozzle be elevated from close proximity to the carpet surface during dusting tool operation and for the reason that cleaners of the particular type disclosed herein, as well as previously, are equipped with rotary agitators having rigid carpet contacting beater bars as well as brushes and, to insure the raising of the nozzle, provision has been made for preventing the insertion of the converter fitting into its port unless the nozzle has been first raised.

This conversion preventing arrangement preferably takes the form of a so-called barrier lever forming an integral part of the pivoted rear wheel support bracket and normally having its end portion protruding into the converter port, so that the converter member cannot be inserted without first removing the barrier. And this of course, can only be accomplished by depressing the rear end of the cleaner body against the tension of the springs acting on the rear wheel support bracket.

But notwithstanding that there is a degree of similarity between the pivoted rear wheel mounting and converter barrier arrangement herein disclosed and that of the earlier disclosure above-mentioned, there are certain features of the present disclosure which are essentially new and meritorious.

In the first place, it will be observed that the handle is mounted near the rear end of the cleaner body and substantially above the rear wheels rather than well forwardly thereof, so that the downward pressure exerted through the handle is more effective in tilting the cleaner. And the second and more important distinction is the character of the springs acting on the rear wheel support bracket. In a word, the springs are now made light enough to yield somewhat under the downward pressure exerted through the handle under ordinary carpet cleaning operations and substantially in direct proportion to the resistance offered to the forward movement of the cleaner by the particular carpet being cleaned. More definitely, there is a range within which the springs will respond to the downward pressure exerted through the handle, thus allowing the cleaner body to tilt just enough to adjust automatically the height of the nozzle

to the character and surface texture of the carpet being cleaned. Thus, if a carpet has a deep thick pile, it follows that a greater resistance would be present to retard the forward progress of the cleaner, and in order to overcome this resistance the operator would have to push harder on the handle and the vertical component of this pressure exerted downwardly at the rear end of the cleaner would tilt the cleaner body about its front wheels and thus elevate the nozzle to its proper height with respect to the carpet.

In this manner, therefore, automatic adjustment of the nozzle is maintained during normal floor cleaning operation. But in addition, it is possible by exerting a still greater pressure through the handle in a downwardly direction to entirely overcome the spring tension, thereby tilting the cleaner body far enough backwardly to swing the obstructing barrier lever away from the converter port and permit the converting operation to be completed.

With this somewhat extended introductory discussion of the object sought to be attained, the novel features of the cleaner will now be described in detail and in connection with the accompanying drawings, in which:

Figure 1 is a general view in side elevation of a suction cleaner embodying the features of the present invention and showing its general arrangement of parts;

Figure 2 is a bottom plan view of the cleaner showing the details of the rear wheel mounting and converter arrangement;

Figure 3 is a view of the cleaner body in side elevation similar to Figure 1 but showing the same tilted into a position indicating the maximum degree of nozzle elevation possible under normal floor cleaning operation and brought about by varying the degree of pressure exerted through the handle;

Figure 4 is a view of the cleaner in side elevation showing the body fully depressed for removing the barrier lever to permit the converter member to be inserted;

Figure 5 is a fragmentary bottom plan view of the cleaner showing the converter member inserted;

Figure 6 is a perspective view of the rear wheel bracket and compression springs; and

Figure 7 is a chart showing the load deflection curve of the compression springs preferably used.

The suction cleaner herein disclosed follows generally the standard design for portable handle-manuevered cleaners, consisting of a main casing 1 including a nozzle portion 2 at its forward end from whence the sides of the casing extend rearwardly with a slight curvature and terminate in an outlet connection 3 at which a dirt bag 4 is removably attached. Pivoted at the rear end of the casing 1 and just forwardly of the outlet connections 3 is the handle 5 adapted to swing forwardly and rearwardly in the usual manner. The only notable feature in regard to the handle is the fact that it is pivoted at a point substantially in vertical alignment with the rear wheels as will be presently seen when the rear wheels are identified.

The suction-creating system of the cleaner consists of the usual motor-driven fan 6 within its chamber 7 located centrally of the casing 1, the driving motor for the fan being housed within a dome-like cover 8 supported on top of the casing 1.

At the center of the bottom wall of the fan

chamber 7 is a circular inlet opening 1a which communicates with the nozzle chamber formed within the nozzle portion 2 of the cleaner casing by means of an air passage formed by shallow side walls 9 depending from the bottom of the fan chamber and a removable bottom plate 10 fitting around the edges of the wall 9.

Extending lengthwise of the nozzle is a rotary agitator 11 consisting of a cylindrical shell having carpet-contacting beater bars 11a and brushes 11b arranged lengthwise of their surface. The agitator is so mounted that the beater bars and brushes project a short distance beyond the downwardly opening nozzle mouth 2a and is adapted to be positively driven by means of a belt 12 extending through the air passage connecting the nozzle chamber with the fan chamber and engaging a pulley 13 forming an extension at the lower end of the hub of the fan 6.

The casing including the aforesaid elements constitutes the body of the cleaner and as such is supported upon pairs of front wheels 14, 14 and rear wheels 15, 15. The front wheels are somewhat larger in diameter and have considerably wider tread surfaces than are generally used because of their ability to support a greater load without sinking into the carpet. These wheels are journaled upon bearings suitably fixed to the casing 1 at opposite sides thereof and just rearwardly of the nozzle.

The rear wheels 15, 15 are located well toward the rear end of the cleaner casing and journaled at opposite ends of a U-shaped bracket 16 which in turn has pivotal mounting on the underside of the casing. As clearly shown in Figure 2, the rear wheel support bracket 16 has a pair of arms 16a, 16a extending forwardly from each end of its main body portion with their extremities practically straddling the rear end of the air passage from the nozzle chamber to the fan chamber. The bracket 16 is preferably stamped from sheet metal and in such manner as to provide a hollow construction throughout with its concaved portions facing upwardly and toward the underside of the cleaner casing. The bracket 16 is pivotally supported at the lower ends of a pair of ears 17, 17 projecting downwardly from the underside of the cleaner casing and carrying hinge pins 17a passing through the arms 16a, 16a inwardly from their ends. The rear wheels 15, 15 are journaled upon stub shafts 18, 18 projecting laterally from opposite sides of the bracket 16.

Between the underside of the cleaner casing 1 and the main body of the rear wheel carrying bracket 16 is introduced a pair of relatively short coil springs 19, 19 with their endmost loops centered on bosses projecting from the surfaces against which the ends of the springs seat, their lower end portions in particular, being well concealed within the U-shaped or channel-like body portion of the bracket. As clearly shown in Figure 6, these springs are spaced apart and well toward the outer ends of the bracket 16 and except for their somewhat unusual conformation are not unlike short compression springs of the coil type.

The springs 19, 19 are designed to respond to certain prescribed degrees of deflection under load, which will be referred to in greater detail later on, but for the present it will be noted that they appear to be fairly, but not excessively, stiff springs of a comparatively few turns but with the diameter of the turns gradually becoming less toward each end. However, considered merely as compression springs, they act to hold the rear

wheel support bracket against movement from its normal position shown in Figure 1, in which the forward ends of the bracket arms 16a, 16a contact the underside of the cleaner casing and necessarily limit the swinging movement of the bracket in one direction.

And in this connection it should be pointed out that one of the bracket arms 16a carries at its end a barrier member which coacts with a converter port (presently to be described) to prevent the conversion of the cleaner to dusting tool operation unless the cleaner body has first been tilted backwardly to elevate the nozzle for the purpose already explained. But before considering the converter obstructing function of the pivoted rear wheel bracket, it may be well to consider and dispose of the first objective sought to be obtained by the herein disclosed spring-tensioned adjustable rear wheel arrangement.

Referring to Figure 1, it is a simple matter to consider the springs 19, 19 serving merely to resist the downward pressure exerted through the handle by the operator as the cleaner is maneuvered in a forward direction over a carpet or other floor covering to be cleaned. Now, with the cleaner standing on a bare surface and with no pressure applied at the handle, it is apparent that the nozzle will assume a normal position with its mouth spaced a predetermined distance above the floor surface as determined by the position of the rear wheels 15, 15. In other words, the springs are capable of counter-balancing the so-called static load and yet are free to yield to a downward force applied through the handle, first, in response to the character of the carpet being cleaned, and second, to a downward pressure applied through the handle when the cleaner is not operating and for the purpose of changing over to dusting tool operation.

For example, in operating the cleaner on a carpet having an unusually deep pile such as found in certain grades of velvet and Chenille carpets, it follows that the supporting wheels sink into the carpet to a greater extent than on carpets having a shorter nap, and naturally the nozzle drops into closer proximity to if not actually into contact with the carpet. Obviously, it requires greater effort on the part of the operator to move the cleaner over the thicker carpet, and this means an increased force exerted through the handle and in a direction to tilt the cleaner backwardly and about the front wheels as a fulcrum. Assuming then, that the springs 19, 19 are gauged to yield to this pressure exerted through the handle, it follows that the cleaner body will tilt backwardly during the forward movement of the cleaner in proportion to the applied pressure thereby raising the nozzle accordingly. Thus, the thicker the carpet the greater the force required to maneuver the cleaner, and the vertical component of this force compressing the springs 19, 19 automatically adjusts the height of the nozzle. Thus there is a range of spring deflections to take care of varying carpet conditions and this range is represented by a predetermined angle through which the cleaner body may tilt from its normal position.

Now, assuming that the only purpose of the compression springs 19, 19 is to offer a uniform yielding resistance to the force exerted through the handle in maneuvering the cleaner over various types of floor coverings and within a prescribed range of adjustment, it would be quite in order to provide a stop member to limit the movement of the wheel carrying bracket 16 when the

maximum position of adjustment had been reached. But the present disclosure contemplates a further tilting movement of the cleaner body beyond that required to attain the automatic nozzle height adjustment just described and for the purpose of completing the operation of converting the cleaner from "on-the-floor" to "off-the-floor" cleaning operation by inserting a converter member into its port. In other words, instead of abruptly limiting the tilting movement of the cleaner within a prescribed range of automatic nozzle height adjustment, the present invention contemplates a still further tilting movement into an extreme position in which it is possible to complete the converting operation, this dual function being likened somewhat to a foot lever which actuates a clutch during a part of its downward movement and operates a brake throughout the remainder.

But in order to bring out this dual functioning of the spring-pressed rear wheel bracket, it will be necessary to describe in some detail the converter arrangement:

Thus, referring to Figures 2 and 4, there will be observed on the underside of the cleaner casing and at the right of the inlet opening to the fan chamber (as it appears in bottom plan view), a hollow conduit 20 extending at right angles to the longitudinal center line of the cleaner body and terminating at its side edge. For all intents and purposes, this conduit is merely a U-shaped member forming the bottom and side walls of a rectangular passageway extending from the outer edge of the casing to the air passage leading to the fan chamber and normally closed at its inner end by a spring-pressed gate or valve 21.

The converter arrangement herein disclosed being in general use and described elsewhere, need not be set forth in detail except to point out that, in the act of inserting a special converter fitting 22 carried at the end of the dusting tool hose into the converter port or passageway formed by the conduit 20, the forward end of the fitting enters the air passageway through the normally closed port and, extending crosswise of the inlet passage immediately in front of the inlet opening to the fan casing, effectively closes off the passageway and simultaneously connects the dusting tool hose directly with the fan chamber, thus transferring the suction from the main nozzle to the dusting tool carried at the outer end of the hose.

Now, as hereinbefore pointed out, it is quite desirable that the cleaner body be elevated sufficiently to remove the agitator from possible contact with the carpet surface during off-the-floor cleaning operation and therefore the completion of the converting operation is made contingent upon the preparatory tilting of the cleaner body and, as hereinbefore suggested, this is accomplished by including a barrier member as a part of the rear wheel support bracket.

Now, referring again to Figure 2, it will be noted that the arm 16a of the hinged wheel carrying bracket 16 on the right of the inlet opening to the fan chamber terminates substantially at the rear edge of the conduit forming the converter port or passage. At the extreme end of this arm is a vertically arranged lug 24 which normally fits within a rectangular notch 26a formed in the lower rearmost edge of the conduit 20 and in this position partially obstructs the conduit as clearly shown in Figure 3, so that it would be quite impossible to insert the converter fitting 22 far enough into the conduit to complete the convert-

ing operation without first removing the obstruction or barrier.

Now, this removal of the obstructing barrier is simply a matter of depressing the rear end of the cleaner downwardly with sufficient force to compress fully the springs 19, 19. (Figure 4.) However, it is to be noted first of all that while it would be possible for the operator to press downwardly directly upon the cleaner body by means of foot pressure or by stooping down and depressing it by hand as is necessary in the previous disclosure referred to, this operation can now be readily performed by raising the handle to its vertical or storage position and then by pressing downwardly on the handle with one hand, depress the rear end of the cleaner while simultaneously inserting the converter member into its port with the other hand. In other words, the operator can perform the converting operation by stooping over instead of kneeling on the floor as he or she might otherwise be tempted to do.

And now, with the dual function performed by the pivotally mounted rear wheel caster bracket clearly in mind, the reason for utilizing springs having a predetermined deflection characteristic will be appreciated and which, incidentally, accounts for their particular formation. In the first place, the springs should yield quite readily under the initial load applied through the handle and so continue throughout a range corresponding to the different types and grades of carpet to be encountered in the average household, but beyond that point to yield only to a substantially increased and especially applied downward force for the purpose of raising the nozzle high enough to displace the barrier and permit the converter fitting to be inserted into its port. Thus, in designing the springs 19, 19, particular regard is given to their so-called deflection characteristic which might be graphically represented by a curve in which load is plotted against deflection and showing a rather uniform deflection throughout the initial range of ordinary operating load conditions and then approaching a more nearly vertical line, indicating an abrupt decreased deflection throughout the range of heavier loads, such as would exist when the operator depresses the rear end of the cleaner preparatory to inserting the converter fitting. Obviously, each of the especially designed springs 19, 19 might readily be replaced with a pair of coacting springs, one functioning throughout the range of automatic nozzle adjustment and the other reinforcing the first-mentioned spring and coming into play as soon as the range of automatic adjustment has been exceeded.

Thus, to summarize the novel features of the present disclosure, the first and primary accomplishment is that of introducing novel means for automatically adjusting the height of the nozzle to the particular type of carpet being cleaned by utilizing the force required to overcome the resistance to the movement of the cleaner over the particular grade of floor covering being cleaned and secondly, combining with the automatic nozzle adjustment the regulation of the converting operation through the medium of a barrier member.

And in this connection, it is obvious that the automatic adjustment of the nozzle height can readily be utilized without making any provision for cleaning with dusting tools. Therefore, it is to be understood that the present invention is not to be limited to the dual arrangement.

Having set forth a preferred embodiment of the invention, I claim:

1. In a suction cleaner of the type having a body including a nozzle at its front end, front supporting wheels positioned rearwardly of said nozzle pivotally supporting said body, rear supporting wheels positioned rearwardly of said front wheels and mounted for vertical movement relative to said body, and a handle pivotally connected to said body above said rear wheels; surface-contacting means on said nozzle adapted to contact and slide over a surface covering undergoing cleaning, resilient means to urge said rear wheels downwardly and to tilt said body about the front wheels with a force equal to the normal component of propelling handle force received thereby with said surface-contacting means sliding over a surface covering with a predetermined optimum frictional resistance, whereby upon said frictional resistance being increased above said optimum and the propelling handle force being thereby increased the said spring receives more than said normal component of force and the cleaner body is tilted in opposition thereto about said front wheels to effect a raising of said nozzle in order to reduce said frictional resistance.
2. In a suction cleaner of the type having a body including a nozzle at its front end, front supporting wheels positioned rearwardly of said nozzle pivotally supporting said body, rear supporting wheels positioned rearwardly of said front wheels and mounted for vertical movement relative to said body, and a handle pivotally connected to said body above said rear wheels; surface-contacting means on said nozzle adapted to exert frictional resistance in sliding contact with a surface covering undergoing cleaning, spring means urging the rear of said body upwardly and said nozzle downwardly into a suction-lifted surface covering thereunder with a predetermined force, said spring means being arranged to oppose the vertical component of the propelling force and having a compression characteristic as to be adapted to be compressed thereby to permit the rear of said body to be lowered and the nozzle to be raised upon the frictional resistance of said surface-contacting means increasing the handle-propelling force beyond a predetermined force.
3. In a suction cleaner of the type having a body including a nozzle at its front end, front supporting wheels positioned rearwardly of said nozzle pivotally supporting said body, rear supporting wheels positioned rearwardly of said front wheels and mounted for vertical movement relative to said body, and a handle pivotally connected to said body above said rear wheels; surface-contacting lips upon said nozzle adapted to exert a frictional resistance in sliding contact with a surface covering undergoing cleaning, a pivoted bracket connecting said rear wheels to said body, a plurality of springs urging said bracket from said body to lower said rear wheels and so to raise the rear of said body with a predetermined force, characterized in that the vertical component of the required propelling handle force is greater than the predetermined force of said springs with said surface-contacting lips exerting more than a predetermined frictional resistance upon sliding over a surface covering undergoing cleaning whereby said springs are compressed and said nozzle is raised to reduce said frictional resistance.
